LINK AND LEVER CONTROLLED
SLIDABLE JAW WRENCH

Harry Wolbaum, Bismarck, N. Dak.

Application October 9, 1951, Serial No. 250,446

1 Claim. (Cl. 81—88)

1

This invention relates to hand tools, and more particularly to improvements in wrenches.

A main object of the invention is to provide a novel and improved wrench which is simple in construction, which is easy to adjust, and which may be employed either as a pipe wrench, or as a monkey wrench.

A further object of the invention is to provide an improved wrench which is inexpensive to manufacture, which is rugged in construction, which is easy to manipulate, and which involves relatively few parts.

Further objects and advantages of the invention will become apparent from the following description and claims, and from the accompanying drawings, wherein:

Figure 1 is a side elevational view with portions of the lower jaw removed of an improved combination wrench constructed in accordance with the present invention.

Figure 2 is a front elevational view of the wrench of Figure 1.

Figure 3 is an enlarged cross sectional view taken on the line 3—3 of Figure 1.

Figure 4 is a longitudinal cross sectional view taken on the line 4—4 of Figure 2.

Figure 5 is an enlarged side elevational detail view of the movable jaw member of the wrench of Figures 1 to 4.

Figure 6 is a cross sectional view taken on the line 6—6 of Figure 5.

Figure 7 is an enlarged cross sectional detail view taken on the line 7—7 of Figure 6.

Figure 8 is a perspective detail view of a modified set of jaw elements which may be employed with the wrench of Figures 1 to 7 on objects wherein it is desired to prevent marring or scratching of the surfaces of the objects to be clamped, one of the jaw elements being shown with a portion of its rubber lining broken away.

Referring to the drawings, the wrench is designated generally at 11 and comprises an elongated main body member 12 having secured to one end thereof the handle 13 and being formed at its opposite end with the arm 14 projecting at right angles to the main portion of body 12, as shown in Figure 1. Designated at 15 is a channel-shaped jaw element which receives the arm 14 and is detachably secured thereto by means of the transverse bolts 16, 16. The jaw element 15 is formed with the transversely extending serrations or teeth 17, defining a jaw face, and with a depending end tooth 18, allowing the jaw to be hooked over an object, such as a section of pipe indicated in dotted view at 19.

2

Designated at 20 is a body provided with a second jaw 21, the jaw body or jaw being mounted on the main bar 12 for sliding movement toward and away from the first jaw 15. The second jaw 21 is opposed to the first jaw 15, and has an inclined top surface 22 inclined outwardly and away from parallelism with the first jaw 15, as is clearly shown in Figures 1 and 4. Slidably mounted on the jaw 21 and receiving the same is the channel-shaped jaw face 23 whose main body portion tapers outwardly in thickness, as clearly shown in Figure 4, and which is provided on its top surface with the transverse serrations or teeth 24 arranged parallel to the teeth 17 on the stationary jaw 15. The side flanges of the channel-shaped jaw face 23 are formed with slots 25 extending parallel to the surface 22, and engaged in the second jaw 21 and extending through said slots are the headed screws 26 acting to retain the jaw face 23 on the jaw 21 but allowing said jaw face to move along the inclined surface 22. The tapered body portion of the jaw face 23 is formed with a depending pin 27 which is received in a cavity 28 formed in the jaw 21 and arranged to limit movement of the jaw face 23 along the jaw 21.

The end portion of the jaw 21 is formed with bores 29 in which are slidably positioned headed pins 30, the heads of said pins being designated at 31 and being biased downwardly, as viewed in Figure 7, by coil springs 32 encircling the shanks of the pins and bearing between heads 31 and the overlying jaw face 23. The bottom surface of the jaw face 23 is formed with recesses 34 in which the end of each pin 30 is receivable, as shown in Figure 7, to lock the jaw face in a fixed position on the jaw 21. The detent pins 30 may be held in locking position by means of a pivoted clip member 35 rotatably secured to the bottom surface of jaw 21 by a headed screw 36 extending through a slot 37 formed in the arched clip 35, as clearly shown in Figure 7. The clip 35 is formed of spring metal and has its rear end 38 abutting the bottom surface of the jaw 21. The flat forward end 39 of the clip is engageable with the ends of heads 31 to hold said heads in fully housed positions in the bores 29 and to maintain the ends of pins 30 in locking engagement in the recesses 34. To release the pins 30, it is merely necessary to rotate the clip 35 away from the position thereof shown in Figure 7, whereby the heads 31 will be allowed to descend under the biasing force of springs 32, disengaging pins 30 from recesses 34 and releasing the jaw element 23.

As will be presently explained, when the jaw

face 23 is released, the wrench may be employed as a conventional Stilson or pipe wrench, and when the jaw face 23 is locked in fixed position on the jaw 21, the wrench may be employed as a monkey wrench.

Designated at 46 is a sleeve member slidably engaged on the bar 12 and formed with the spaced arms 41 and 42. The rear margin of bar 12 is formed with the rack teeth 43. Rotatably mounted on a pin member 44 secured in the arms 41 and 42 parallel to the bar 12 is a worm 45 meshingly engaged with the rack teeth 43, as is clearly shown in Figures 1 and 4. Designated at 46 is a lever member pivotally connected at 47 to the movable jaw body 20 and formed with the offset handle portion 48. Designated at 49 is a link bar pivotally connected to the sleeve member 40 at 50 and pivotally connected to the intermediate portion of lever 46 at 51, as shown in Figure 1. Threadedly engaged in the link bar 49 is the stop screw 52 whose head is arranged to abut the forward surface of the bar 12. The screw 52 may be adjusted so that the head thereof will engage the bar 12 when the lever 46 has been rotated to a position just beyond dead center in a clockwise direction, as viewed in Figure 1, whereby the linkage will be locked with the jaws of the wrench tightly engaged with the object to be gripped.

When an object is to be gripped by the wrench, as for example, a round object such as a pipe 19, the object is first engaged beneath the hook jaw 15, the lever 46 is swung inwardly until the head of screw 52 abuts bar 12, and the worm 45 is rotated until the jaw face 23 engages the bottom surface of the object 19. The handle 48 may then be swung outwardly, and the worm 45 may then be rotated further for an amount depending upon the degree of tightness of the desired gripping action. The handle 48 may then be swung inwardly, causing the linkage defined by members 46 and 49 to be rotated past their dead center positions, as above described, wherein the head of screw 52 abuts bar 12, causing the jaw faces 17 and 23 to tightly engage on the object 19. In the case of a round object, such as the pipe 19, the slidable jaw face 23 may be left free to move along the inclined surface 22, and the wrench may be employed as a pipe wrench, whereby the gripping action of the jaw elements is increased as torque is applied to the handle 13 by the wedging action provided when the movable jaw face 23 is forced inwardly on the inclined surface 22. However, should it be desired to employ the wrench as a monkey wrench, the jaw face 23 may be locked in stationary position relative to the jaw 21 by employing the clip 35 to hold the pins 39 in interlocking engagement with recess 34 in the manner above described, whereby face 23 is held against movement relative to the jaw 21.

Figure 8 illustrates a pair of jaw elements 15' and 23' which may be employed in place of the jaw faces 17 and 23 of Figure 1 when the device is to be employed for gripping surfaces, such as polished metal surfaces, wherein marring or scratching of the surfaces must be avoided. The upper jaw element 15' is provided with a gripping surface member 60 which may be formed of rubber or similar deformable resilient material and the lower jaw element 23' is similarly provided with a gripping surface member 61 of rubber or similar material. The gripping elements 60 and 61 clampingly engage the object to be held and may engage said object with any desired degree of tightness, determined by the adjustment of 75

the worm 45 in the manner above described, without marring or scratching the surfaces of the object thus held. When it is desired to employ the device merely as a pipe wrench, the clip 35 and its fastening screw 36 may be omitted, as well as the pins 39 and their biasing springs 32, as shown for example in Figures 1 and 2.

In order to provide a balanced detent action on the movable jaw face 23, a pair of locking pins 30 are preferably provided, spaced symmetrically on opposite sides of the longitudinal center line of the jaw 21, as shown in Figure 6, the clip 35 being of sufficient width to simultaneously engage the head portion 31 of both pins 30, 30.

As shown in Figures 3 and 4, the movable jaw face 23 is biased inwardly by a coiled spring 62 which bears between the depending pin element 27 and a machine screw 63 threaded through the end of the arm jaw 21. If so desired, the spring 62 may be removed by merely removing the screw 63, whereby the jaw face 23 is free to slide on the jaw 21 over a range of movement determined by the length of the recess 28. However, the spring 62 is preferably employed to bias the jaw face 23 inwardly, since said spring acts to urge the jaw element into gripping position at all times, assuming that the worm 45 has been properly adjusted with respect to the object to be gripped.

While a specific embodiment of an improved combination wrench device has been disclosed in the foregoing description, it will be understood that various modifications within the spirit of the invention may occur to those skilled in the art. Therefore, it is intended that no limitations be placed on the invention except as defined by the scope of the appended claim.

What is claimed is:

40 A wrench comprising an elongated body member, a first jaw projecting laterally from said member and rigidly secured to said member, a second jaw projecting laterally from said member and opposing said first jaw and mounted on said member for sliding movement toward and away from said first jaw, a link and lever mechanism operatively connected to said second jaw for controlling the limit of movement of said second jaw toward said first jaw and locking said second jaw in such limit of movement position, a 45 jaw face superimposed upon said second jaw and connected to said second jaw for movement toward and away from said member, said second jaw being provided with a longitudinally extending cavity in the part facing said first jaw, a pin depending from said jaw element and extending into said cavity, and spring means carried by said second jaw and bearing against said pin for biasing said jaw face toward said member.
